Primary Examiner — Paula Allen Greene(74) *Attorney, Agent, or Firm* — Michael Best and Friedrich LLP(57) **CLAIM**

The ornamental design for a headphone as shown and described.

DESCRIPTION

FIG. 1 is a perspective view of a headphone showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof; and,

FIG. 8 is an enlarged perspective view thereof along the lines 8-8 and 8'-8' of FIG. 1.

The broken lines illustrating portions of the headphone form no part of the claimed design.
